CYLINDER MOLD FOR PAPERMAKING MACHINES

George A. Engert, North Hoosick, N. Y.

Application November 21, 1949, Serial No. 128,655

1 Claim. (Cl. 92—43)

1

This invention relates to improvements in paper making machines and particularly relates to a new and useful cylinder mold construction for high-speed cylinder paper machines.

In such machines, a foraminous cylinder mold having a fine mesh woven wire outer surface, revolves partially submerged in a vat pond of water and paper stock mixture.

The stock consists of vegetable fibers reduced by acid or alkali process or by mechanical means to hair-like particles of cellulose ranging in length from one millimeter to one and a quarter millimeters. These particles or fibers of cellulose are then mixed with water, generally to form a consistency of one half of one percent solids to water. Clay, starch, resin size, coloring matter, alum and other "loading" chemicals are added, the choice depending on the properties desired in the finished paper. This mixture is then flowed or pumped to the vat into which the foraminous cylinder rotates.

Usually the cylinder is from 10 to 12 feet long with a series of internally spaced supporting spiders. The ends of the cylinder are sealed to the sides of the vat so that water in the paper stock flows through the fine wire cover of the cylindrical surfaces into the inside of the cylinder. A sheet of cellulose fibers is thus deposited on the face of the cylinder. Water is drawn from the inside of the cylinder forming a "differential head" of pressure between the inside and the outside of the cylinder to further draw liquids from the vat and deposit solids on the cylinder face.

The speed in forming a sheet of paper by this method is limited to the rate at which water in the stock outside the cylinder can be drawn through the screen face into the cylinder. It is known that a lighter consistency of solids to water in the paper stock will make a better sheet. However, to gain this lighter consistency, a larger volume of water must be drawn from the stock. Cylinders heretofore used have not been capable of drawing the larger volume of water without appreciably slowing the rate of speed.

The speed of such prior cylinder machines is limited to a sheet formation at a rate of approximately four hundred feet of paper per minute. Beyond this speed centrifugal force tends to throw the formed sheet off the wire face of a cylinder. The supporting structure of spokes and rods inside the cylinders agitate the water in the cylinder interior at such higher speeds forcing the water outwardly through the cylinder face. Thus distortion occurs in the sheets being formed. In addition churning of the water retards the angular

2

velocity of the cylinder and interferes with the proper drainage of water from the interior cylinder.

An object of this invention is to provide a cylinder mold construction which will form a stronger sheet of paper from a lighter consistency of paper stock and water and to do so with a minimum of "grainage" at a speed greatly in excess of the speeds now obtained by conventional molds for this purpose.

Another object of my invention is to provide a smooth hollow cylinder free from internal spokes, spiders, cross-bars, vanes, rods or other obstructions which cause agitation, turbulence, and foam as the cylinder rotates in the vat mixture.

A further object is to provide a cylinder mold with a smooth interior surface and having full length internal suction chambers in a new arrangement longitudinally of the cylinder open to specific arcuate areas of the inner surface so as to draw fibers onto the cylinder and water from the sheet being formed for the speedier and more effective formation of the paper web.

A still further purpose is to provide a pressure box chamber to assist in dislodging the formed sheet more rapidly in transferring the same from the cylinder onto the under side of the usual felt conveyor belt for further drying and processing.

Other objects and advantages will be apparent from the following description and drawings, in which:

Fig. 1 is a more or less diagrammatic view in perspective of a new cylinder as installed in a vat, with suction couch roll and traveling felt also indicated;

Fig. 2 is an elevational view showing a cylinder mold in the tank as in Fig. 1 with parts broken away for clarity;

Fig. 3 is a sectional view taken on line 3—3 of Fig. 2;

Fig. 4 is a fragmentary sectional view taken on line 4—4 of Fig. 3 to show details of the sealing ring and cylinder face construction;

Fig. 5 is a cross section of the cylinder with parts removed taken on line 5—5 of Fig. 2 to show suction box arrangement;

Fig. 6 is a perspective view, in broken section, of the cylinder; and

Fig. 7 is a perspective view on reduced scale of the wall arrangement for suction boxes with the cylinder.

As shown by Fig. 1, a cylinder 10 is rotatably contained in a stock vat 11 having a series of adjustable making boards 12. Paper stock is fed into the vat as shown by the flow arrows, while

the cylinder 10 is revolving, to almost totally submerge the cylinder. As stock attempts to penetrate the cylinder face, wire mesh screen 13 on the face of the cylinder 10 strains out the stock solids and the water filtrate drains into the interior of the cylinder where it is pumped off through outlet 14 in one side of the vat. The solid material which collects and settles on the wire mesh 13 emerges as a wet sheet on the mold at the stock level near the top of the vat. Across the top of the cylinder 10 a felt web 15 is drawn and the wet sheet is lifted from the mold surface by the web. At the point of contact, a couch suction roll 16 of the usual construction draws further water out of the wet sheet.

Cylinder 10 is supported by two end spiders 17 (Figs. 2 and 3). Spiders 17 are provided with hollow hubs 19 and 20 which extend through the sides of vat 11 and are supported thereby. Both hubs are journaled in the vat sides and are freely rotatable therein. A stationary pipe 21 is supported in the hubs as an axle and extends between the sides of the vat. Pipe 21 is closed at one end by a cap 22 and is connected at its other end to a vacuum pump arrangement as will be described.

Hub 19 of spider 17 is slightly elongated and carries a spur gear 23 for driving engagement with a variable speed gear drive mechanism (not shown) so as to revolve cylinder 10 about stationary pipe 21. Bearing bushings 24 are interposed between each hub and the pipe 21.

The supporting shell of the new cylinder is formed by a cylindrical plate 25 (Fig. 6) attached to rims 26 of the two spiders. Plate 25 is perforated with large closely spaced openings 27 for free drainage of water into the interior of the cylinder. Closely spaced longitudinal rods 28 are affixed as by countersinking on plate 25 and are held as by riveting. They extend the length of the cylinder between the spider rims 26. Transversely of rods 28 and wrapped around the cylinder are a series of closely spaced wires 29. The woven cylindrical wire screen 13, covers wires 29 and is of approximately 40, 50 or 60 mesh as may be desired.

Inside cylinder 10, the lower half of the stationary pipe 21 is perforated (see Fig. 5) so as to form a suction tube for "drawing a vacuum" in the interior of the submerged lower portion of the cylinder. Longitudinal walls or partitioning plates 30 and 31, extending the full length of the cylinder between the two rotating end spiders, divide the cylinder interior into upper and lower compartments. The wall plates 30 and 31 are fixed to the pipe 21 and extend radially from the pipe. Gaskets 32 at their outer edges abut the inner surface of shell plate 25 to provide a sealing contact.

Rims 26 of the spiders are flanged and a complementary circular flange or chime ring 33 (Fig. 4) extends from each side of vat 11. A liquid tight rubber ring 34 seals the space between these flanges and prevents any of the vat contents from entering the interior of the cylinder except through its foraminous wall. Screw clamps 35 as shown by Figs. 2 and 3 are fixed to the vat side and hold ring 34 stationary. The clamps also are threaded to provide for tension adjustment.

A "differential head" is created in a lower compartment 36 of the cylinder, as formed by the plates 30 and 31, by water being pumped out of this compartment through the outlet 14 in the side of vat 11. The pressure differential pulls paper stock against the lower segment of

the rotating cylinder thus drawing water through the cylinder's peripheral openings into the lower compartment 36 which water in turn is pumped out through outlet 14.

The open end of pipe 21 provides a conduit for connection to a suitable vacuum pump and suction created in pipe 21 is exerted in lower compartment 36 through the perforations in the lower half of pipe 21. The partial vacuum in the lower compartment 36 assists in drawing a greater amount of water from the sheet being formed on the face of the cylinder and further helps in the rapid forming of the sheet against the face.

In the upper half of the cylinder provision is made for three chambers or sections 37, 38 and 39 (see Fig. 7) by two vertically disposed longitudinal wall plates 40 and 41 fixed to pipe 21 and extending radially therefrom. These plates also have sealing gaskets 32 at their outer edges to abut the revolving inner surface of the shell plate 25. Semi-circular end walls in the upper half of the cylinder adjacent the spiders as at 42 in Fig. 4 close the ends of sections 37, 38 and 39.

A suction tube 43 located within tube 21 is connected to section 37 by branches through the wall of tube 21 adjacent section 37 so as to create a vacuum of slightly different degree in this section than is drawn in the lower compartment through the larger suction pipe 21. The "vacuum" drawn in section 37 is preferably slightly greater and is for the purpose of further sheet formation and to eliminate wash and slippage of the formed wet sheet as it leaves the stock level in the vat at the point of emergence as will be described. At this location on the cylinder facing the inlet side of the tank the sheet is stronger and can stand somewhat more "suction" without affecting its proper formation.

Section 38 is of appreciably smaller volume, covers less cylindrical surface and provides a pressure chamber for the cylinder. It is located at the top of the cylinder where the wet sheet contacts the felt web 15 at the "nip" of the couch roll 16. This chamber is supplied with pneumatic pressure from a pressure line as a tube 44 placed inside pipe 21. Tube 44 has branches as at 45 to section 38 so as to direct the air under pressure toward the "nip" of the couch 16 and assist in the removal of the wet sheet of paper from the cylinder onto the felt web 15.

The third section 39 in the upper portion of the cylinder lies between plates 30 and 41 and is blanked off so that pipe 21 for compartment 36 will not have connection to the top of the cylinder on this side and the atmosphere. The wall 30 is at the mid line of the vat so that stock level in the vat can diminish to that point without affecting the desired vacuum pressure in lower compartment 36.

In Figs. 2 and 3 it will be noted that sealing caps 46 are provided at each end of the vat to seal the exposed part of the cylinder from the atmosphere at each end between the edge of the cylinder and the tank.

Plate 25 with its relatively large perforations is of sufficient strength together with the longitudinal rods 28 to be self sustaining when mounted on the end spider construction as described. The inner surface of the plate 25 being smooth creates less turbulence and permits the use of the suction boxes or chambers as described.

The speed possible with the new cylinder is

appreciably greater than that possible with usual high speed cylinder mold constructions. In operation the formation of the sheet on the mold is assisted first by suction in the lower compartment in addition to the usual "differential" and secondly by the slightly greater degree of suction created in the section chamber 37 where the wet sheet emerges from the level of stock in the vat. Furthermore, the speed of sheet formation is not affected by the usual limitations of speed at which the sheet may leave the cylinder. Air pressure at the "nip" of the couch roll may be controlled to enable a faster take off as may be desired onto the traveling felt web.

Having described my invention, I claim:

A cylinder mold for operation in the stock vat pond of a paper making machine comprising a hollow cylindrical shell having a series of closely spaced relatively large openings in the wall thereof and a smooth inner and outer surface, supporting spiders solely at the ends of said shell, a stationary pipe of relatively small diameter throughout supporting said shell, hubs on said spiders journaled on said pipe, a plurality of spaced rods fixed longitudinally on the outer surface of the shell, closely spaced, transverse wires encircling said rods and a wire mesh screen covering over said wires in closely spaced relation to said shell, the interior of said shell being compartmented into four chambers, horizontally disposed flat walls extending longitudinally of the shell and laterally from each side of said pipe and fixed thereto to form a lower semi-cylindrical chamber, said stationary shell supporting pipe having a suction passage therethrough and suction ports in the wall of said pipe communicating with said lower chamber, a flat vertically disposed wall fixed to the pipe on the upper surface thereof and extending radially to the inner surface of said shell to form with

one of said horizontal walls and therebetween an inlet side of said cylinder shell, a second pipe longitudinally disposed within said shell supporting pipe and forming a second suction conduit, said second pipe having suction port conduits communicating through the wall of the shell supporting pipe between said latter walls for creating a second suction chamber for the inlet side of said shell, a flat wall closely spaced from said vertical wall and on the outlet side of the same to form therebetween a pressure chamber, a pressure conduit in said pipe and ports therein communicating with said pressure chamber, the chamber formed by said last-named wall and the horizontal wall at the outlet side of said shell being closed and preventing communication at said outlet side with any of said other chambers, semi-circular end walls adjacent said spider supports closing off the ends of said chambers in the upper portion of said shell and sealing gaskets at the outer ends of the walls abutting the smooth inner surface of the shell.

GEORGE A. ENGERT.
